MEDICAL EXAMINATION TABLE OR THE LIKE

Karl H. Burzlaff, Fairport, and Egon R. Weickgenannt,
Rochester, N.Y., assignor to Ritter Company Inc.,
Rochester, N.Y., a corporation of Delaware

Filed May 5, 1964, Ser. No. 79,826

Term of patent 14 years

(Cl. D83—1)

FIG. 1

FIG. 2

Des. 200,377

PAGE 2

FIG. 3

FIG. 4

FIG. 5

FIG. 6

FIG. 1 is a top plan view of our design for a medical examination table or the like;

FIG. 2 is a left-hand side elevational view looking from the right-hand end of the table as viewed in FIG. 1;

FIG. 3 is a bottom plan view of our table shown in FIG. 1;

FIG. 4 is a right-hand side elevational view looking from the right-hand end of the table as viewed in FIG. 1;

FIG. 5 is a right-hand end elevation view of our table shown in FIG. 1; and

FIG. 6 is a left-hand end elevational view of our table as shown in FIG. 1.

We claim:

The ornamental design of a medical examination table or the like, substantially as shown.
